DESIGN FOR A PORTABLE CONTAINER FOR FOOD PRODUCTS OR THE LIKE

Charles B. Arnold, Chicago, Ill., assignor to The Greif Bros. Cooperage Corporation, Cleveland,
Ohio, a corporation of Delaware

Application May 25, 1940, Serial No. 92,591

Term of patent 14 years

To all whom it may concern:

Be it known that I, Charles B. Arnold, a citizen of the United States, residing at Chicago, in the county of Cook and State of Illinois, have invented a new, original, and ornamental Design for a Portable Container for Food Products or the like, of which the following is a specification, reference being had to the accompanying drawing, forming part thereof, wherein:

Figure 1 is a view in perspective of a portable container for food products or the like, showing my new design; and

Fig. 2 is a top plan view thereof.

I claim:

The ornamental design for a portable container for food products or the like, as shown.

CHARLES B. ARNOLD.
